The ornamental design for a battery charger for cellular phone batteries, as shown and described.

DESCRIPTION

FIG. 1 is a top view of the battery charger for cellular phone batteries of the present invention;

FIG. 2 is a left side view of the battery charger for cellular phone batteries of FIG. 1;

FIG. 3 is a front view of the battery charger for cellular phone batteries of FIG. 1;

FIG. 4 is a rear view of the battery charger for cellular phone batteries of FIG. 1;

FIG. 5 is a right side view of the battery charger for cellular phone batteries of FIG. 1; and,

FIG. 6 is a bottom view of the battery charger for cellular phone batteries of FIG. 1.

FIG. 1

FIG. 2

FIG. 3

FIG. 4

FIG. 5
